UNITED STATES PATENT OFFICE.

WILLIAM W. MAJOR, OF MIDLOTHIAN, TEXAS.

TIRE-PATCH FOR INNER TUBES.

1,128,256.

Specification of Letters Patent.

Patented Feb. 9, 1915.

Application filed July 31, 1914. Serial No. 854,219.

To all whom it may concern:

Be it known that I, WILLIAM W. MAJOR, a citizen of the United States, residing at Midlothian, in the county of Ellis and State 5 of Texas, have invented certain new and useful Improvements in Tire-Patches for Inner Tubes, of which the following is a specification.

My invention relates to patches for the inner tubes of pneumatic tires, and the object is to provide a simple device for jacketing that part of an inner tube which may be adjacent to a puncture or weak place in the outer casing to prevent blow outs of the 5 inner tube, that is, to prevent the inner tube from being pressed into punctures in the outer casing or shoe. The patch will also close punctures in the inner tube, and is used as an emergency device. Another 0 object is to provide means for holding the patch in place without mutilating the inner tube or the outer casing or shoe and to provide flexible means for securing the patch on the inner tube and for hingedly connecting the 5 meeting portions of the patch together so that the patch will hold the inner tube safe in the outer casing. Other objects and advantages will be fully explained in the following description and the invention will 0 be more particularly pointed out in the claims.

Reference is had to the accompanying drawings which form a part of this application.

Figure 1 illustrates a portion of an inner tube of a pneumatic tire, showing the inner face or circle with a patch applied thereto. Fig. 2 is a cross-section, taken on the line $x-x$ of Fig. 1 and showing the tire applied to a wheel rim. Fig. 3 is a broken longitudinal section of an inner tube with a part of a patch, showing the contraction of the inner tube when a patch is used on the inner tube.

Similar characters of reference are used to indicate the same parts throughout the several views.

A portion of an inner tube 1 is shown provided with a patch 2. Fig. 2 shows the inner tube 1 and the patch 2 inclosed in a tire casing or shoe 3 which is applied to a wheel rim 4. The edges 5 and 6 of the patch lap past each other and the edge 5 terminates in a feather edge, as shown in Fig. 2. The patch 2 being constructed of elastic material and the longitudinal edges lapping

past each other, the patch will make a perfect seal. The end edges 7 of the patch also terminate with feather edges so that there will be no abrupt bending of the inner tube and the natural contraction of the tube will be gradual. The patch 2 is secured on the inner tube by a hinge connection. Strips 8 and 9 of soft and flexible leather are doubled and attached to the patch 2 by stitching, 65 as shown in the drawings, or otherwise suitably attached to the patch. The meeting edges of the leather hinge are cut away alternately to form bearings 10 and 11 for a pintle 12. The bearings 10 and 11 are 70 thus interlocked and the bearings are formed by the doubling of the leather strips 8 and 9 and the pintle 12 is run through the interlocked portions or bearings 10 and 11. The strips 8 and 9 thus become the jaws of 75 a hinge and the pintle 12 completes the hinge so that the edges of the patch are hingedly connected. One end of the pintle 13 is bent over the edge of one of the hinge jaws. This is necessary for inserting and 80 removing the pintle. The other end 14 of the pintle terminates at the middle point or approximately the middle point of the bearing 15 so that there will never be any danger of the end of the pintle mutilating 85 the inner tube or the patch. For this reason the bearings 15 are made much longer than the bearings 10 and 11. The strips 8 and 9 are made shorter than the tube 1 so that the strips are spaced from the ends of the 90 tube. This will provide a flexibility in the ends of the patch. This will prevent chafing of the inner tube about the ends of the patch. The strips 8 and 9 are preferably 95 made of flexible leather, but it is apparent that other flexible tough material may be used for this purpose. The hinging of the strips 8 and 9 together renders the patch flexible at all points so that the flexibility of the inner tube is not impeded by the 100 patch.

What I claim, is,—

1. A tire patch and guard for the inner tube of a pneumatic tire consisting of a sheet of elastic material formed into a tube 105 with the edges of the sheet lapping past each other and a flexible hinge therefor consisting of strips of flexible material attached to said patch near the lapped edges thereof and having interlocking bearings on their 110 meeting edges and a pintle running through all of said bearings except one and termi-

- inating near the longitudinal center of the last bearing, whereby said last bearing forms a guard to prevent the mutilation of the inner tube by the end of the pintle.
- 5 2. A tire patch for the inner tube of a pneumatic tire consisting of a sheet of flexible material formed into a tubular member with the edges thereof lapped past each other and the inner edge terminating with 10 a feather edge and a flexible hinge connection for said tubular member to secure the same on the inner tube consisting of soft tough leather strips doubled to form bearings and the free edges attached to said 15 tubular member near the lapped edges thereof and the meeting edges of said folded strips being cut away to form interlocking bearings, and a pintle running through all 20 said bearings except the last and said pintle terminating at the middle point of the last bearing.

3. A tire patch for the inner tube of a pneumatic tire consisting of a sheet of flexible material formed into a tubular member with the edges thereof lapped past each 25 other and the inner edge terminating with a feather edge and a flexible hinge connection for said tubular member consisting of soft tough leather strips attached to said tubular member near the lapped edges there- 30 of and spaced from the ends of the tubular member to permit easy coöperation of the tubular member with the inner tube and having interlocking bearings, and a pintle running through said bearings. 35

In testimony whereof, I set my hand in the presence of two witnesses, this 23rd day of July, 1914.

WILLIAM W. MAJOR.
